UNITED STATES PATENT OFFICE

2,633,506

SELECTIVE CIRCUIT MAKER

Carlos Wittenmyer, Lebanon, Ohio

Original application January 6, 1944, Serial No. 517,154, now Patent No. 2,493,709, dated January 3, 1950. Divided and this application November 26, 1949, Serial No. 129,623

4 Claims. (Cl. 200—4)

1

The present invention relates to circuit makers and breakers and more specifically to a circuit maker and breaker for use in cases where there are a plurality of potential circuits each for operating a different instrumentality, and it is desired to complete a pre-selected one of such circuits.

The present application is a division of pending application Serial No. 517,154, filed January 6, 1944, now Patent No. 2,493,709, issued January 3, 1950, by the present inventor on Automatic Typewriters.

In this prior application there is shown mechanism for attachment to a typewriter whereby by actuation of a single key a sequence of characters, for example, a date or time of day or other data, is typed. This attachment is electrically actuated and involves a plurality of circuit makers and breakers.

Among the objects of the present invention is a circuit maker and breaker particularly suitable for this purpose.

Another object is the provision of a device of the kind indicated in which there are a plurality of potential circuits of which one may be selected for completion.

Other objects and advantages will be apparent to those skilled in the art upon reference to the following description and the accompanying drawings in which

Fig. 1 is a schematic representation and wiring diagram of accessory apparatus for use with an electrically actuated typewriter.

Fig. 2 is an elevation, with part in section, of one of the number wheel switches.

Figs. 3 and 4 are elevations of parts of the latter.

Figs. 5 and 6 are respectively end and side elevations of a hand operated switch operating means.

Fig. 7 is a schematic representation of a device similar to that of Fig. 1 but adapted for calculating machines.

Fig. 8 is a view showing a row of keys of a calculating machine and the interacting contacts connected therewith.

In the drawings (Fig. 7) there is shown at 29 a device consisting of a casing having mounted therein an oscillatable arm 21 carrying at its free end an electric contact member 21A adapted to touch in turn a plurality of contacts 21B insulated from each other and arranged in an arc. The arm 21 extends radially from a friction wheel or roller 22 a portion of which protrudes from the casing and is adapted to contact a suitable

2

portion of a typewriter carriage (not shown) at the will of the operator.

The contact 21A is connected through the arm and lead 21C to a mercury switch 23 and thence to a suitable source of power. Each of the contacts 21B will also be connected electrically as will be described below.

Referring now to Fig. 1, a sequence device such as is above briefly described, is shown at 10 120, and as in Fig. 7 the contact carrying swinging arm 121 will be connected to a suitable source of electricity, while each of the stationary contacts 121B will be connected to a suitable connection on a gang member 25 from which corresponding connections lead to the several discs 28. These discs 28 constitute a part of the switch mechanism claimed herein and shown in detail in Figs. 2 to 5.

As shown in these figures, the switch consists of the disc 26 mounted coaxially with a second and third disc, the second disc 27 being shown as a numbered wheel having extending axially through it a plurality of rods 27A which project from both faces and are arranged in a circle. There will be one rod of electricity conducting material while the others serve to dynamically balance the disc. The third disc 28 will be coaxial with discs 27 and 26 and be made of suitable electrically conductive material or covered therewith on the face presented to disc 27.

The disc 26 will be made of non-conducting material and having extending axially through it or suitably mounted in that face adjacent disc 27 as many conducting rods or contacts 26A as there are characters on discs 27 and located the same radial distance from the center as the rods 27A in disc 27, so that the one electrically conductive rod is in position to contact any one of contacts 26A.

If the device is intended to type automatically the time of day, for example, 10:22 a. m., the discs 27 will be provided with suitable numbers and letters and punctuation marks and will be rotated by a master clock and indexed by conventional mechanism (not shown).

If on the other hand, the device is intended to type the results of the operation of a calculating machine, the discs 27 will be geared to the rotatable accumulator wheels of the machine and the discs 26 will be maintained against rotation. In either case, when the discs 26 and 27 have assumed their proper relative position and it is desired to complete the circuit, the two discs 26 and 28 are moved toward disc 27 until the con-

ductive rod 27A contacts the disc 28 and one of the electrical contacts 26A.

As indicated above, the discs 28 are each connected to one of the contacts 21B or 121B.

The contacts 26A will be connected to suitable solenoids adapted to actuate the typewriter keys corresponding to the characters to be printed. So, when the potential circuits have been set up by the rotation of wheels 27, actuation of arm 21 or 121 by the typewriter carriage completes such circuits in turn.

In the case of the use of the device with a calculating machine, the latter will be provided with accumulator wheels geared to wheels 27. Further, the keys of such a machine will be so arranged that only one key in a row will be active in setting up a potential circuit. Such an arrangement is shown in Fig. 8.

In Fig. 8 there is shown a row of keys 30 corresponding to the number of columns on the calculating machine and intended for use in the printing operation. These keys 30 are each provided with an arm 32 so arranged that the operation of any key will also move all of those switches to the left, breaking circuit A and closing circuit B, this being accomplished by means of cams 30A on the keys 30. The keys all pass through a slotted bar 31 which is moved to the left by the cam 30A on the depressed key.

Each of the keys 30 is arranged to operate a two-way switch which normally completes a circuit from the central member 33 through the arm 33A, but when the key is depressed, breaks this circuit and completes a circuit through the arm 33B.

The location and operation of these switches 33 is shown in Fig. 7. In this figure, the sequence means 20 has its contacts 21B connected to the several central arms 33 of the key switches and the arms 33A are connected to the discs 28 at the counting wheels 27, while the arms 33B are connected to solenoid S, this being the solenoid for actuating the typewriter spacer key. Therefore, when it is desired to omit printing of the four left hand columns for example, the key 30 opposite the fourth column from the left is depressed. This bypasses the impulse from these four columns to the typewriter spacer key. The next column, however, will print as will all of the columns to the right of the depressed key.

In Figs. 5 and 6 there is shown one structure for moving the discs 26 and 28 into contact with wheel 27. In these figures, the slotted bar 31 (shown also in Fig. 8) is shown as a rack geared as by gear 39 to a second bar 40, so that movement longitudinally of either will move the other in the opposite direction, while both may be moved through the operation of the handle 41 fixed to the gear 39.

Bars 40 will be provided with arms 42 carrying discs 26 and the other, 31, with arms 43 carrying discs 28.

I claim:

1. A register for a counting machine including a rotatable number wheel, a non-rotatable disc adjacent thereto and provided with electric contacts equal in number to the numbers repre-

sented by said wheel, a single contact extending through and projecting from the sides of said wheel, a metallic disc adjacent said wheel at the side opposite said first disc, and means for moving said discs simultaneously toward or away from said wheel whereby to complete or break an electric circuit between said metallic disc and one of the contacts carried by the other disc.

2. A register for a counting machine including a rotatable number wheel, a non-rotatable disc adjacent thereto and provided with electric contacts equal in number to the numbers represented by said wheel, a single contact extending through and projecting from the sides of said wheel, a metallic disc adjacent said wheel at the side opposite said first disc, means for moving said discs simultaneously toward or away from said wheel whereby to complete or break an electric circuit between said metallic disc and one of the contacts carried by the other disc, and means for distributing over the faces of said discs the pressure exerted by said discs against the sides of the wheel.

3. A circuit maker and breaker consisting of a plurality of plate-like members arranged coaxially and in parallel relation, a plurality of elements extending through the intermediate plate and projecting from the faces thereof, one of said elements being a conductor, a plurality of contacts carried by one of the outer plates, means for moving relatively the latter plate and the intermediate plate whereby to arrange the single conducting element opposite a selected one of said plurality of contacts, means connecting said selected contact and the third plate into a potential electric circuit and means for moving the contact carrying plate and said third plate against the elements of the intermediate plate.

4. A circuit maker and breaker consisting of a plurality of coaxially arranged discs, the first consisting of conducting material, the second consisting of non-conducting material having a plurality of elements extending axially therethrough and arranged in a circle, one of said elements being a conductor and the third plate consisting of non-conducting material having a plurality of conductors extending therethrough and opposite the circle of elements in the second plate, means for relatively rotating the second and third plates whereby to place said conducting element opposite a selected one of the conductors carried by the third plate, and means for moving said plates into contact.

CARLOS WITTENMYER.
